MANDREL

Harry Hamilton Moran, Bayside, N. Y.

Application October 11, 1944, Serial No. 558,185

10 Claims. (Cl. 93—59)

1

This invention relates to new and useful improvements in expanding or contracting mandrels used primarily, though not exclusively, in the manufacture of containers. One embodiment of mandrel of the present invention has particular application in the forming of a lined container of special construction forming the subject matter of my co-pending application, Serial No. 558,186, filed of even date herewith.

This container comprises, generally speaking, an outer package, receptacle, box, bag, or the like, having an inner packaging unit or liner which is preferably adhesively joined over all or a major portion of its outer surface to the inner surface of the outer packaging receptacle, except, of course, for the filling opening. The outer unit will ordinarily be made of relatively heavy cardboard, or other semi-rigid material, whereas the liner is preferably formed from thin, moisture-impervious sheet material, such as regenerated cellulose, glassine paper, metal foil, or the like. In other instances, however, the outer unit may also be made from paper or other thin flexible material.

One method of forming the container of my co-pending application consists in first forming the outer unit, and then inserting the blank forming the liner element by the use of the expanding mandrel constituting the present invention. The blank may be formed simultaneous with the step of inserting the same within the outer unit, or, in some instances, it may constitute a preformed unit in the nature of a bag. The outer surface of the liner element is provided with an all-over coating of some suitable adhesive, or it may have an all-over coating of a thermo-plastic or thermo-setting material, or, in some instances, the liner element may be formed from a sheet of the thermo-plastic or thermo-setting material. The formed, or partially formed, liner element is carried by the mandrel into the outer unit, whereupon the mandrel expands, firmly pressing all parts of the liner element into firm adhesive engagement with the inner surface of the outer unit, the walls of which may be suitably supported by external pressure plates. In the event that the thermo-plastic or thermo-setting coating or element is employed, suitable heat-transfer means will be associated with the mandrel, although in a case of ordinary adhesive, the heating element may be dispensed with.

Another method of forming the container is to first form the liner element over the mandrel while in its fully-expanded position, then forming the outer unit over the liner and firmly press-

2

ing the outer walls into engagement with the liner element, and finally retracting the walls and corner sections of the mandrel to permit easy withdrawal of the mandrel from the finished container.

Expanding mandrels have, of course, been known, but the devices of the prior art have failed to firmly press all portions of the surface of the liner element into firm engagement with the outer unit. In the corner sections, particularly, there has been an absence of complete contact, thus causing the liner to bridge over the corner sections, causing pockets which are easily ruptured by the contents. The liner element in containers of this character is preferably a relatively thin, delicate membrane which requires the support afforded by the relatively stronger and more rigid walls of the outer unit, and in the event that gaps or pockets occur between the two walls, even a fair measure of rough handling causes the inner wall to become ruptured, and permits the contents, should they be liquid, to leak out, and, in the case of packaged frozen foods, permits oxidation of the foods and loss of moisture therefrom, which in a relatively short time considerably reduces their quality.

Some expanding mandrels of the art have provided means for properly forming the corner sections, but leave considerable gaps between the corner sections which frequently cause as much trouble as do the pockets in the corners. The expanding mandrel of the present invention has means whereby all parts of the corner sections, as well as the intervening side walls and bottom walls, are pressed firmly into engagement with the inner surface of the outer unit, thereby forming a completely laminated or unitary wall structure. In other words, the mandrel in its fully-expanded position presents four continuous side walls and a continuous bottom wall, except for minor openings adjacent the corner sections which are immaterial.

One embodiment of a mandrel of the present invention includes a frame structure made up of a plurality of superimposed frame elements suitably held together, certain of these frame elements supporting a plurality of vertical edge bars for longitudinal, reciprocating movement. Another of these frame elements supports the lower, horizontal edge bars, and still others support the face plates. Boxes of the character previously referred to are generally square or rectangular in horizontal section, and the vertical edge bars are journaled in the appropriate frame elements for diagonal, reciprocating movement at an angle of

45° to the surfaces of the vertical face plates. The inner surfaces of these corner edge bars may be convexly curved, and the edges of the face plates ride around these curved surfaces during outward movement of such plates. Both the edge bars and the plates, however, are positively driven outwardly, although if the corner edge bars are convexly curved, as just mentioned, positive outward driving movement of such edge bars is not necessary, since they are moved outwardly due to a camming action of the edges of the face plates against these curved surfaces. In this case, the corner edge bars may be retracted by spring means, or other suitable means such as the tracks interlocking with the face plates, or stops connected with the edge bars activated by retraction of the face plates.

The mandrel is further formed with lower horizontal edge bars which may also be formed with concave surfaces, such lower edge bars being carried at their terminals by the corner edge bars. A bottom face plate is caused to move downwardly by a positive drive, and if desired, such downward movement may be the sole means for moving the horizontal corner edge bars outwardly. Of importance in the present invention is the fact that the vertical edge bars and the lower, horizontal edge bars move to their full downward position before any outward movement of any of the edge bars or face plates occurs. In some of the devices of the prior art, outward movement of certain of the portions of the mandrel is accompanied by downward movement as well, which tends to tear the liner and destroy its effectiveness. The mandrel of the present invention, however, moves all portions of the liner element to their full downward position, and, accordingly, the only further movement of the liner element is directly outwardly.

Another important object of the invention is to provide a heated, expanding mandrel wherein outward movement of the side plates trails outward movement of the edge bars, thus leaving an air space between said walls and the liner before final pressing, and preventing premature activation of the thermally-active material.

In the drawings:

Fig. 1 is a vertical section taken through an expanding mandrel of the present invention, the section being taken on line 1—1 of Fig. 2.

Fig. 2 is a horizontal section taken on line 2—2 of Fig. 1.

Fig. 3 is a horizontal section taken on line 3—3 of Fig. 1, such view showing only the vertical edge bars and face plates.

Fig. 4 is a fragmentary, perspective view, partially in section, taken on line 4—4 of Fig. 2.

Fig. 5 is a broken perspective view showing the relation of the vertical edge bars to the horizontal edge bars.

Fig. 6 is a top plan view of the frame element which supports and causes outward movement of the vertical face plates.

Fig. 7 is a bottom plan view of such frame element.

Fig. 8 is a broken perspective view showing one of the terminals of the frame element illustrated in Figs. 6 and 7.

Fig. 9 is a fragmentary, perspective view of the upper corner section of the top plate and a vertical edge bar.

Fig. 10 is a perspective view of the upper terminal of an edge bar.

Fig. 11 is a fragmentary, perspective view of

an edge bar showing an alternative method of retracting the vertical edge bars.

Figs. 12 and 13 show another alternative method of retracting the vertical edge bars.

The mandrel of the present invention includes a plurality of vertical edge bars 10, a plurality of horizontal edge bars 11, vertical face plates 12 and 13, and a bottom face plate 14. The foregoing elements are supported in a frame structure which is carried at the lower end of an impelling shaft 15 which may be carried by a suitable vertically-reciprocating plunger. The lower end of the impelling shaft is threaded, as shown at 16, and receives an internally-threaded collar 17 which carries an externally-threaded block 18 at its lower end, the several frame elements being secured to such block. Frame elements 21 and 22 support the vertical face plates 12 and 13, and frame elements 23 and 24 support the vertical edge bars 10. A filler block 25 of any suitable depth may be carried between frame elements 23 and 22.

Block 18 is formed with a plurality of apertures 27 which receive headed bolts 28 which pass through aligned apertures 29 in the several frame elements and the filler block. The apertures in lower frame element 21 are threaded, as shown at 30, which receive the lower threaded terminal of bolts 28. If desired, of course, a nut could be placed at the lower end of the bolts to engage the lower surface of frame element 21. Additional support for the frame structure is afforded by means of a bolt 33 which is threaded at its upper end, and carries a nut 34 positioned between the upper end of block 18 and the lower end of impelling shaft 15. This bolt passes through aligned apertures 35 in the several frame elements, the lower end of the bolt being threaded, as shown at 36, and being received within a threaded opening 37 in frame element 23.

It was pointed out that frame elements 23 and 24 support the vertical edge bars 10. A top plan view of frame element 23 is illustrated in Fig. 2, and is formed with diagonal extensions 40 having vertical slots 41 therein which form bifurcated supports, which receive inner extensions 42 of the vertical edge bars 10. These extensions may be formed integrally with the edge bars, as indicated in Fig. 4, or they may be welded or otherwise secured thereto. Bifurcated supports 40 are provided with aligned curved slots 44 having the contour illustrated in Fig. 4, although they may, if desired, have straight sides and be positioned at an angle to the vertical. Each extension 42 carries a pin 45 which is positioned within such slots 44. It will be seen from the foregoing that when the lower terminals of vertical edge bars 10 are moved downwardly through downward movement of impelling shaft 15 to a point where they engage the lower walls of the inner and outer package elements, they cease any further downward movement, but further downward movement of the impelling shaft causes the pin 45 to ride upwardly relative to slot 44, thus producing outward travel of the edge bars.

At its upper end, the mandrel is provided with a cap 48 having at each corner thereof an elongated slot 49. A pin 50, shown in detail in Fig. 10, which is carried at the upper end of edge bar 10, passes through slot 49 and forms a sliding connection between the edge bar and cap 48. This pin is generally rectangular in transverse section, and is provided with a head 51 which engages the upper surface of cap 48.

It was earlier pointed out that edge bars 10

are formed with convexly-curved inner surfaces 52. This surface may, if desired, be straight, thus providing an edge bar which is triangular in transverse section, or it might be an angled plate. By providing the convexly-curved surface, however, there is a cooperation between outward movement of the face plates 12 and 13, and such edge bars, as will be pointed out more in detail hereinafter. The opposed, vertical edges of the face plates are bevelled, as shown at 53.

Plates 12 and 13 are supported in frame elements 21 and 22, which are shown in detail in Figs. 6, 7 and 8. Such frame elements are formed with right-angular extensions 55 having terminal portions 56 of reduced width, such extensions being shorter at their upper ends than at their lower ends by providing a diagonal wall 57, shown clearly in Fig. 8. Such extensions are provided with diagonal slots 58 which receive pins 59 carried by bifurcated extensions 60 secured to, or formed integrally with, face plates 12 and 13. The upper surface of each horizontal edge bar 11 is flat, as shown at 63, and the lower edge 64 of face plates 12 and 13 rides outwardly on such upper surfaces. It will accordingly be seen that after the lower terminals of vertical edge bars 10 have reached their maximum downward position, and further downward travel of the frame structure causes outward movement of the vertical edge bars, such movement is accompanied by conjoint outward movement of face plates 12 and 13 due to the cam action of slots 58 acting against pins 59, and the outer, vertical edges 65 of the bevelled surfaces 53 of face plates 12 and 13 ride outwardly on the curved surface 52 of vertical edge bars 10.

The means for mounting and actuating the horizontal edge bars 11 will now be described. Outer surface 67 and lower surface 68 of each edge bar 11 lie at right angles to each other, and the inner edge 69 is convexly curved up to the point 70, and thereabove, edge 71 may be substantially straight and inclined outwardly. At each end thereof, edge bar 11 is formed with a horizontal bore 74 which receives a horizontal pin 75 rigidly carried adjacent the lower end of each vertical edge bar 10. It will accordingly be seen that as vertical edge bars 10 travel diagonally outwardly, they carry with them horizontal edge bars 11, and such outward movement of edge bars 11 is aided by downward movement of lower face plate 14, which will now be described.

A post or stud 78 is mounted centrally on the upper surface of lower face plate 14, and at its upper end is provided with a horizontal aperture 79 which receives a pin 80 which travels in a short, vertical slot 81 in an aperture 82 in frame element 23. A coiled spring 86 carried concentrically of stud 78 urges face plate 14 downwardly. It will accordingly be seen that stud 78 is movable upwardly relative to aperture 82 against the compression of spring 86. The marginal edge 90 of lower face plate 14 is bevelled, and normally engages the inclined edge 71 of horizontal edge bar 11, as shown in Fig. 1. When vertical edge bars 10 and horizontal edge bars 11 have initially moved downwardly to their maximum position, the parts are in the position shown in Fig. 1. Further downward travel of the impelling shaft causes vertical edge bars 10 to move outwardly, as previously described, thus also drawing horizontal edge bars 11 outwardly, and such movement is aided by downward movement of face plate 14 due to spring 86.

When the impelling shaft is moved downwardly to a point wherein the lower terminal 91 of elong-

ated pin 33 engages the upper terminal 92 of stud 78, further downward movement causes the stud to be driven positively downwardly to a point wherein the lower surface of horizontal face plate 14 engages the bottom wall of the container. When the parts are fully retracted, end walls 94 of horizontal edge bars 11 are in contact with walls 95 formed at the lower end of vertical edge bars 10. In order to accommodate the corner sections of bottom plate 14, the lower terminal of each vertical edge bar 10 is formed with a curved surface 96 on each inner side thereof, such curved surface forming a continuation of curved surface 69, and a substantially square, cut-out portion 97, all as shown in Fig. 5.

From the foregoing, it will be seen that as the vertical and horizontal edge bars 10 and 11, respectively, move outwardly to their expanded position, the edges of lower plate 14 ride downwardly over surfaces 96 in vertical edge bars 10, as well as surfaces 69 in horizontal edge bars 11. In fully expanded position, there will be a slight gap between walls 94 and 95, although this is immaterial from a practical point of view, since the heat, in case of the heated element, will bridge over such a small area, and in the case of wet adhesive, sufficient pressure is applied to the area during outward movement of the parts to effectively adhere the two wall sections together.

In the event that the thermo-plastic or thermo-setting material is to be employed, the inner surfaces of the several plates may have heating elements affixed thereto, such as is shown at 100 in the case of side plate 12, and 101 in the case of bottom plate 14. No details of the construction of such heating elements are shown, for the reason that this construction is well known in the art. Also, if desired, heating elements may be associated with the vertical and horizontal edge bars.

In forming a container of the type previously described, it will be appreciated that the liner element will extend above the outer packaging unit proper. Whether or not any portion of this liner is to be adhesively secured to the closure flaps at the upper end of the container is a matter of choice. In any event, in most instances the overlapping seams in the liner unit may extend from the lower end of the container upwardly on two opposed side walls, such as the side walls engaged by opposed side wall plates 12. It will, accordingly, be necessary to apply heat and/or pressure to that portion of such seams as extend above the container, and not, however, to apply heat and/or pressure to those portions of the side walls of the liner lying on opposite sides of the seams. In order to accomplish this result, the upper ends of plates 12 may have inwardly-set portions 104, and a central portion 105 which is substantially planar with the balance of the outer surface of such plates 12. This will leave recesses 106 on opposite sides of central portion 105 which will not engage the surface of the liner element, although central portion 105 will engage such element at the overlapping seams, firmly compressing such seams between portions 105 and the outer pressure plates which engage the outer surfaces of the outer unit. The cap 48 may have downwardly-extending flanges 107 which limit outward movement of side plates 12 and 13.

A compression spring 108, carried concentrically of shaft 15, engages plate 48 at its lower end, and a stop pin (not shown) further up shaft 15. This spring retains the plates and edge bars 75 in retracted position until further downward

movement of the shaft occurs. The spring also acts to retain the mandrel in downward position as the shaft starts its upward movement, thus preventing upward movement of the side plates and edge bars until the same are retracted. If, on the other hand, a retracting, as distinguished from an expanding, mandrel is desired, the spring will normally be under tension by securing the spring at its lower end to the cap, and to the pin at its upper end, the spring in this instance being somewhat shorter than the compression spring.

Referring to Fig. 1, it will be noted that the outer surface of central portion 105 is on the same plane as the balance of the outer surface of plate 12. In some instances, it may be desirable, however, to etch, machine, or otherwise reduce outer surface 105 an amount equal to the thickness of the liner material. Also, at the lower end of the container wherein four thicknesses of the material are in overlapping relation, it will be desirable to etch the surface lying adjacent to such overlapping portions an amount equal to three thicknesses of the liner material. Also, in the event that windows are formed in the outer container, appropriate openings may be made in the side plates adjacent to such openings.

In the modified form of the invention illustrated in Fig. 12, the vertical edge bar 110 is carried solely by adjacent side plates 111, and, in this instance, some form of trackway, such as is shown at 112, is carried by, or is formed integrally with, the vertical edge bar 110. This trackway is curved, as shown, and is received within an appropriately-formed opening 113 formed in each side plate 111. When in retracted position, the bevelled edge 114 of plate 111 engages the similar bevelled edge of the adjacent plate, and inward movement of the face plates 111 brings with them the edge bars 110 into retracted position. As plates 111 move outwardly to expanded position, edge bars 110 likewise move outwardly.

Another modified construction which accomplishes substantially the same result is illustrated in Figs. 12 and 13, wherein edge bar 116 is formed at its inner surface with a curved extension 117, a shank 118, and stop members 119. In this case, side plates 120 have bevelled edges 121, and in retracted position, the parts occupy the relation shown in Fig. 12. As plates 120 move outwardly, such outward movement is imparted to the vertical edge bars 116, and thus bring the outer faces of plates 120 into the same plane as the outer faces of edge bar 116 when in fully expanded position.

The expanding or contracting mandrel of the present invention has been illustrated in the drawings, particularly in Fig. 1, as being vertically movable on a suitable support or impelling shaft 15. In many instances, however, it will be desirable to have the mandrel horizontally movable rather than vertically. For convenience, in the appended claims the shaft and the frame structure will sometimes be defined as being vertically movable, although it is to be clearly understood that such reference does not preclude the possibility that the structure otherwise defined in such claims may be horizontally movable rather than vertically, should this be desired.

It was earlier pointed out that one of the principal objects of the invention was to provide a novel mandrel wherein the movement of the side and bottom plates to expanded position trailed movement of the corner bars to expanded position. It will be appreciated from the foregoing

description that many advantages accrue from such an arrangement. For instance, when the parts of the mandrel are still in retracted position, there will be a considerable air spaced between the side and bottom plates and the walls of the liner element, and, accordingly, the thermally-active coating will not begin to be activated until the plates have moved to expanded position. Also, the fact that the edge bars move outwardly before the plates permits the corners of the liner element to be moved to final position before any pressure is exerted against the side walls due to the action of the side plates. This arrangement also prevents the possibility of sealing the vertical seams 44 before the mandrel is fully expanded.

The initial expansion action caused by outward movement of the edge bars permits the liner to slip around them, and, accordingly, position all parts of the liner element in proper relation to the outer packaging unit. This is especially important in cases wherein the thermally-active materials are used. Since the edge bars are in contact with the liner element before the side walls move to expanded position, these edge bars are in contact with the liner element for a longer period of time, and thus permit a lower degree of heat in the edge bars. In other words, thermal activation of the side wall portions of the liner element is delayed until all parts of such element are in proper position. This also permits a higher degree of heat to be used in the side plates, and consequently produces a faster laminating cycle than if the same heat is maintained as is maintained in the edge bars. No heating element is shown which is directly associated with the edge bars, and, in most instances, heat transfer from the side plates to such edge bars is sufficient. Nevertheless, heating elements may be carried on the edge bars.

Whether the mandrel of the present invention is employed as an expanding or a contracting device, the operation is substantially the same, except for the rearrangement of the spring 108 previously noted. It is important to note that at the end of either operation, and when the parts of the mandrel are contracted for removal, there is no movement of any part in the nature of a wiping action against the walls of the liner. Such a wiping action has accounted for bad results in the form of pin holes, tears, ruptures, and the like, in the prior mandrels of this general type. In the present mandrel, the side and bottom walls move perpendicular to the walls of the liner, and the edge bars leave the walls of the liner directly even though diagonally.

The particular contour of slots 44 and 58 is, of course, a matter of choice, and this contour may be varied to suit different conditions. Also, the upper slots may have one contour and the lower slots another, all for the purpose of retracting the upper or the lower end of the side plates or vertical edge bars more rapidly than the opposite end.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the inven-

tion may be made without departing from the principles thereof.

What I claim is:

1. An expanding mandrel for adhesively pressing a box liner in contact with the box, comprising a frame, a vertically-reciprocable supporting means for the frame, a plurality of vertical edge bars carried by the frame and being movable outwardly to expanded position in a direction diagonally of the frame, lower edge bars and side plates carried by the frame and being outwardly movable at right angles to the frame, and a bottom plate being downwardly movable along with movement of the side plates, the mandrel providing substantially unbroken side and bottom walls when the parts are in expanded position, and cam means for moving the bars and plates to expanded position upon downward movement of the supporting means after the edge bars have been lowered to box-engaging position.

2. A mandrel of the character described comprising a frame, means for supporting the frame, a plurality of vertical edge bars and lower, horizontal edge bars, a plurality of side plates carried between the vertical edge bars, and a bottom plate carried between the horizontal edge bars, the frame being provided with means for supporting the bars and plates for reciprocating movement, cam means for moving the vertical edge bars diagonally outwardly relative to the frame and for moving the side plates and the horizontal edge bars outwardly in a direction at right angles to the frame during outward movement of the vertical edge bars, and means for simultaneously moving the bottom plate downwardly.

3. An expanding mandrel of the character described comprising a frame, means for supporting the frame, a vertical edge bar at each corner of the frame and a lower, horizontal edge bar on each side of the frame, side plates carried intermediate of the vertical edge bars, and a bottom plate carried intermediate of the horizontal edge bars, cam means for moving the vertical edge bars diagonally outwardly, means for moving the side plates and the horizontal edge bars outwardly in a direction at right angles to the frame during outward movement of the vertical edge bars, and means for moving the bottom plate downwardly.

4. In an expanding mandrel for lining boxes, the combination of a frame, means for supporting the frame and for lowering it into box-engaging position, a bottom plate which is movable downwardly and a plurality of side plates which are movable outwardly at right angles to the bottom plate, all carried by the frame, a plurality of vertical edge bars movable outwardly diagonally of the frame to form, when the side plates and vertical edge bars are in expanded position, unbroken side walls, and a plurality of lower, horizontal edge bars which are movable outwardly at right angles to the frame upon outward movement of the vertical edge bars, cam means carried by the frame for moving the side plates and vertical edge bars outwardly, upon further downward movement of the supporting means, and means carried by the frame for moving the bottom plate downwardly to box-engaging position.

5. In an expanding mandrel for lining boxes, the combination of a frame, a vertically-reciprocable supporting element for the frame, a plurality of elements carried by the frame including side plates movable outwardly at right angles to the frame, a bottom plate movable downwardly,

vertical edge bars movable outwardly diagonally of the frame to form, when the side plates and vertical edge bars are in expanded position, unbroken side walls, and a plurality of lower, horizontal edge bars carried by the vertical edge bars and being movable outwardly at right angles to the frame upon outward movement of the vertical edge bars, cam means carried by the frame for moving the side plates and vertical edge bars outwardly after the latter have been moved downwardly to engagement with the lower wall of the box, and means carried by the frame for moving the bottom plate downwardly to a point wherein its lower surface is planar with the lower surface of the horizontal edge bars.

6. In an expanding mandrel for lining boxes, the combination of a frame, a vertically-reciprocable supporting element for the frame, a bottom plate which is movable downwardly and a plurality of side plates which are movable outwardly at right angles to the bottom plate, a plurality of vertical edge bars movable outwardly diagonally of the frame to form, when the side plates and vertical edge bars are in expanded position, unbroken side walls, and a plurality of lower, horizontal edge bars which are movable outwardly at right angles to the frame upon outward movement of the vertical edge bars, journal means carried by the frame for supporting the bars and plates during outward and inward movement, cam means for moving the side plates and horizontal edge bars outwardly after the latter have been moved downwardly to box-engaging position, and means carried by the frame for moving the bottom plate downwardly to box-engaging position.

7. A mandrel of the character described for laminating boxes, comprising a frame, side and bottom plates journaled in the frame for reciprocating movement substantially at right angles to the frame, vertical edge bars journaled in the frame for reciprocating movement diagonally of the frame to form continuous side walls for the mandrel when the parts are in expanded position, and lower, horizontal edge bars carried at the lower terminals of the vertical edge bars and being outwardly movable upon outward movement of the latter, supporting means for the frame for lowering such frame into box-engaging position, cam means carried by the frame for moving the side plates and edge bars outwardly, and means for moving the bottom plate downwardly.

8. A heated mandrel of the character described for laminating boxes, comprising a frame, side and bottom plates journaled in the frame for reciprocating movement substantially at right angles to the frame, vertical edge bars journaled in the frame for reciprocating movement diagonally of the frame to form continuous side walls for the mandrel when the parts are in expanded position, heating elements associated with the side and bottom plates, and lower, horizontal edge bars carried at the lower terminals of the vertical edge bars and being outwardly movable upon outward movement of the latter, supporting means for the frame for lowering such frame into box-engaging position, cam means carried by the frame for moving the side plates and edge bars outwardly, such cam means being actuatable by further downward movement of the supporting means, and a spring carried by the latter for normally holding the parts in retracted position, and means for moving the bottom plate downwardly.

9. An expanding mandrel for adhesively press-

ing a box liner in contact with the box comprising a frame, a vertically-reciprocable supporting means for the frame, a plurality of vertical edge bars carried by the frame and being movable outwardly to expanded position in a direction diagonally of the frame, lower edge bars carried by the vertical edge bars and side plates carried by the frame and being outwardly movable at right angles to the frame, the vertical edge bars being formed with two liner-engaging edges joined by a third, convexly-curved edge, the opposed vertical edges of the side plates engaging such convexly-curved edge during outward movement, thus moving said edge bars outwardly, a bottom plate being downwardly movable along with movement of the side plates, and cam means for moving the side plates to expanded position upon downward movement of the supporting means after the edge bars have reached the lowermost position, said supporting means moving the bottom plate downwardly.

10. An expanding and contracting mandrel for making boxes and the like, such mandrel comprising a frame, a plurality of vertical edge bars carried by the frame and being movable outwardly to expanded position in a direction diagonally of the frame, lower edge bars and side plates carried by the frame and being outwardly movable generally at right angles to the frame, and a bottom plate being downwardly movable along with outward movement of the side plates, the mandrel providing substantially unbroken side and bottom walls when the parts are in expanded position, vertically-reciprocable means for supporting the frame, and means connecting the frame with the outwardly and downwardly movable parts for moving such parts to expanded position after the mandrel has reached its lowermost position.

H. HAMILTON MORAN.
